FIRE EXTINGUISHER

Howard Waters Doughty, Amherst, Mass., assignor to Firetox Company, Holyoke, Mass., a corporation of Rhode Island

Application September 16, 1947, Serial No. 774,353

3 Claims. (Cl. 169—26)

1

This invention relates to fire extinguishers and particularly to improvements in extinguishers which are adapted to release a fire extinguishing agent automatically when the temperature in the vicinity of the apparatus rises to a predetermined point.

In apparatus of this type, a receptacle is provided for a fire extinguishing liquid, usually a chlorinated hydrocarbon such as carbon tetrachloride and a gas generating agent such as an aqueous solution of ammonia. The apparatus is provided with a sprinkler head or similar distributor and an outlet leading thereto which is normally sealed and adapted to be released when a fire occurs. Pressure is developed by the gas generating agent when the temperature rises, and the fire extinguishing agent is forced through the outlet when the latter is released. The fire extinguishing agent is distributed over the surrounding area.

The receptacle in such extinguishers is customarily made of aluminum to avoid corrosion by the liquid contents as described in Patent No. 1,698,840. Usually such extinguishers are provided with the "dual control" features of Patent No. 1,736,255. In recent forms of such extinguishers, parts of the release mechanism have been constructed of stainless steel, as shown for example in Patent No. 2,020,427. The extinguishers may be constructed so that the fire extinguishing liquid is delivered upwardly through an outlet tube as shown, for example, in the last mentioned patent.

The frangible diaphragm which is characteristic of the "dual control" feature of Patent No. 1,736,255 may be made of any suitable metallic foil of requisite strength, but usually gold foil is employed. The diaphragm is secured between two washers of suitable material, stainless steel being commonly used. The diaphragm prevents the escape of any liquid from the extinguisher until the pressure therein has risen to a point sufficient to rupture the diaphragm. The latter is ordinarily protected by means which prevents rupture until a link or cap has likewise been released by an increase of temperature sufficient to melt a low melting point alloy whereby the link or cap is held in place. Consequently the liquid is not released until the temperature is sufficiently high to melt the alloy and also to generate gaseous pressure within the container.

In extinguishers such as I have described, the aluminum comprising the receptacle is relatively high in the electropotential series, whereas both gold and stainless steel (iron 74%, chromium 55

2

18%, nickel 8% or similar composition) are relatively low in the same series. The liquid contents of the extinguisher afford an excellent electrolyte and consequently over a period of years electrolytic corrosion may occur and eventually will cause failure of the device if a closed circuit is maintained, permitting the flow of current between the gold, stainless steel or other similar metal and the aluminum.

10 It is the object of the present invention to avoid, in fire extinguishers of the type described, the effects of electrolytic corrosion and consequent failure of the apparatus.

15 Other objects and advantages of the invention will be apparent as it is better understood by reference to the following specification and the accompanying drawings, in which

Fig. 1 is a sectional view through an extinguisher embodying the invention; and

20 Fig. 2 is an enlarged sectional view of the sprinkler head in such an extinguisher.

As an example of the invention, and referring to the drawing, a receptacle 5 is made of aluminum to avoid the chemical corrosive effect of the mixture of carbon tetrachloride and aqueous ammonia which is stored in the receptacle. In the form of the invention illustrated, the liquid is discharged upwardly through a tube 7. The tube 7 is connected to a plug 8 threadedly secured in 30 a head 9 having a yoke 10 and a distributor 11 mounted thereon. The tube 7, the plug 8 and the head 9 may be made of aluminum and are secured in an opening in the casing 5 by a collar 12 also of aluminum.

35 Supported in the head 9 is a thimble 13 which in the present form of the invention is also made of aluminum and is adapted to receive a cap 14, preferably of stainless steel covering an outlet 15 and held in place by a low melting point solder 16 around the edges of the cap. The thimble 13 is filled preferably with a material 17 which is liquid or semi-liquid at the temperature at

40 which the apparatus is designed to operate. Vaseline and glycerine are suitable materials. Low melting point waxes and like materials can be used. The material 17 is designed to be ejected when the diaphragm is released to permit the expulsion of the liquid contents of the receptacle. It serves meanwhile to protect the dia-

45 phragm hereinafter described and to prevent rupture thereof until the cap 14 is released by the melting of the solder.

50 Between the flange at the lower end of the thimble 13 and the shoulder formed by the inner end of the plug 8, the diaphragm assembly is

mounted. It consists of a diaphragm 18 of aluminum foil. It is mounted between washers 19 and 20 also of aluminum, which hold the diaphragm firmly and prevent leakage of liquid around it so that no liquid can escape until the diaphragm is ruptured.

As will be seen from the foregoing, all of the parts of the extinguisher, except the cap 14, which are exposed to liquids or vapors of ammonia and carbon tetrachloride, are made of aluminum, and hence there is no difference of potential between the parts and no electric current can flow between them in the presence of the electrolyte. Therefore, no electrolytic corrosion is possible, and extended life of the apparatus is assured.

In order to hold the cap 14 in place so that it will be released only at a suitable temperature, low melting point solders such as Woods metal, Rose metal, Lipowitz metal, etc. are used. These solders do not adhere readily to aluminum. To avoid this difficulty, I plate the end of the thimble 13 with a suitable metal such as copper, brass, nickel or silver. Any of these metals can be deposited on the surface of the aluminum by ordinary electroplating, or otherwise, and the coating affords a satisfactory base to which the low melting solder will readily adhere. I prefer to plate the end of the thimble 13 with silver, since this metal is not affected by the mixture of liquids such as carbon tetrachloride and aqueous ammonia or by their vapors, whereas nickel is very slightly and slowly affected and copper and its alloys may be dissolved in time by contact with such liquids and vapors. Nevertheless copper, brass and nickel will serve the purpose of affording a satisfactory base for the application of low melting point solder, since the cap is not normally in contact with the contents of the extinguisher.

The improved extinguisher as described is relatively inexpensive as compared with forms of such devices heretofore in use, and since there is no possibility of electrolytic corrosion, the apparatus can be maintained in use for many years without possibility of failure.

Various changes may be made in the structure and arrangement as described without departing from the invention or sacrificing the advantages thereof.

I claim:

1. In an automatic fire extinguisher adapted to release a fire-extinguishing liquid under pressure generated by increase in temperature in the vicinity of the extinguisher to a predetermined point and comprising a receptacle for the fire extinguishing agent and pressure generating agent, an outlet assembly connected to the receptacle and having a discharge passage therethrough and including an outlet thimble and means normally sealing the discharge passage but adapted to burst when the pressure within the container reaches a predetermined point, the improvement in which the outlet thimble and the other parts of the outlet assembly are of aluminum so that

there is no difference of potential between the parts thereof, the outlet thimble has its exposed end coated with a metal of the class consisting of copper, brass, nickel and silver, and a cap is secured to the coating by a low melting point solder.

2. In an automatic fire extinguisher adapted to release a fire-extinguishing liquid under pressure generated by increase in temperature in the vicinity of the extinguisher to a predetermined point and comprising a receptacle for the fire extinguishing agent and pressure generating agent, an outlet assembly connected to the receptacle and having a discharge passage therethrough and including an outlet thimble and a diaphragm of aluminum foil normally sealing the discharge passage but adapted to burst when the pressure within the container reaches a predetermined point, the improvement in which the outlet thimble and the other parts of the outlet assembly are of aluminum so that there is no difference of potential between the parts thereof, the outlet thimble has its exposed end coated with a metal of the class consisting of copper, brass, nickel and silver and a stainless steel cap is secured to the coating by a low melting point solder.

3. In an automatic fire extinguisher adapted to release a fire-extinguishing liquid under pressure generated by increase in temperature in the vicinity of the extinguisher to a predetermined point and comprising a receptacle for the fire-extinguishing agent and pressure generating agent, an outlet assembly connected to the top of the receptacle and having a discharge passage therethrough and including an outlet thimble, means normally sealing the discharge passage but adapted to burst when the pressure within the container reaches a predetermined point and a discharge tube extending from the outlet assembly to adjacent the bottom of the receptacle, the improvement in which the receptacle, the discharge tube and the outlet thimble and the other parts of the outlet assembly are of aluminum so that there is no difference of potential between said parts, the outlet thimble has a coating at its exposed end of a metal of the class consisting of a copper, brass, nickel and silver and a cap is secured to the coating by a low melting point solder.
